UNITED STATES PATENT OFFICE.

ARTHUR F. BENT, OF SWAMPSMOTT, MASSACHUSETTS, ASSIGNOR TO G. W. BENT CO.,
OF BOSTON, MASSACHUSETTS, A CORPORATION OF MAINE.

CRIB.

1,293,001.

Specification of Letters Patent.

Patented Feb. 4, 1919.

Application filed July 19, 1917. Serial No. 181,540.

To all whom it may concern:

Be it known that I, ARTHUR F. BENT, a citizen of the United States, and a resident of Swampscott, in the county of Essex and State of Massachusetts, have invented an Improvement in Cribs, of which the following description, in connection with the accompanying drawings, is a specification, like characters on the drawings representing like parts.

This invention relates to metallic cribs for children and has for its object to provide a strong yet light crib, which is provided with a side frame capable of being raised and lowered with relation to the mattress-supporting frame and also capable of being folded over upon the mattress-supporting frame, whereby the crib is especially adapted for use in small or narrow quarters as will be described. The invention further has for its object to provide the crib with a supporting device of novel construction, which is employed to support the vertically movable side frame.

The metal crib is also provided with novel structural features, which permit the crib to be folded up into small or compact form and which render the crib firm and substantial when in use, as will be described.

These and other features of this invention will be pointed out in the claims at the end of this specification.

Figure 1 is a side elevation of a metal crib embodying this invention.

Fig. 2, a like elevation of a portion of the crib showing the movable side in its lowered position.

Fig. 3, a plan view of the crib shown in Fig. 1.

Fig. 4, a plan view of the crib in its folded up condition.

Fig. 5, an enlarged elevation and transverse vertical section of the crib in its folded up condition, and

Fig. 6, a detail of the supporting device for the movable side frame, to be referred to.

Referring to the drawing, *a*, *b*, represent the head and foot frames; *c*, *d*, the side frames, and *e* the mattress-supporting frame of a metal crib embodying this invention.

The head frame *a* is composed of two members 10, 12, (see Fig. 3), which are connected by suitable hinges or pivots 13, and the foot frame *b* is composed of like mem-

bers 14, 15, connected together by like hinges 55 or pivots 16. The members 10, 14, may be considered as stationary and the members 12, 15, as movable and capable of being turned toward each other into a position substantially at right angles to the members 10, 14, (see Fig. 4), when the crib is not in use.

The stationary members 10, 14, are connected by the rear side member *c*, which may and preferably will be rigidly attached to said stationary head and foot members 10, 14, to thereby obtain greater stiffness and strength.

The side member *d*, which may designate the front side member, is connected with the mattress-supporting frame *e* in such manner 70 as to be capable of bodily movement vertically with relation to said mattress-supporting frame and also capable of pivotal movement with relation thereto, so that when the crib is in its operative position, the front side 75 member *d* may be extended above the mattress-supporting frame to close the crib at its front side, as shown in Fig. 1, or it may be dropped or lowered so as to leave the front side of the crib practically open as 80 shown in Fig. 2, so as to give convenient access to a child in the crib, and when the crib is in its inoperative condition, the side member is folded over upon the mattress-supporting frame and is capable of being moved 85 with the latter into a substantially vertical position substantially parallel with the rear or stationary side member, as shown in Figs. 4 and 5. The front side member *d* also cooperates with the head and foot frames to be 90 guided thereby in its vertical movement and is capable of detachment therefrom to leave it free to be folded over upon the mattress-supporting frame.

In the present instance, the movable side 95 member *d* is composed of top and bottom cross bars 20, 21, and vertical rods 22 connected therewith. It is pivotally connected to brackets 23 attached to the mattress-supporting frame *e* near the opposite ends thereof (see Fig. 1), which is effected by pivot rods 24 mounted to turn in the brackets 23 and provided with eyes 25, through which the endmost vertical rods 22 are extended and are capable of sliding therethrough to 100 permit the side frame *d* to be moved in a vertical path from its raised position shown in Fig. 1, into its lowered position shown in

Fig. 2. Provision is made for guiding the side frame *d* in its vertical movement, which is effected as herein shown by providing the top cross bar 20 with eyebolts 27, which engage stationary guide rods 28 attached to the head and foot frames, said eye-bolts being provided with slots or openings 29 of less width than the diameter of the guide rods 28, (see Fig. 3), and which coöperate with reduced portions 30 of the upper ends 31 of the rods 28 (see Figs. 1 and 3) to permit the eye-bolts 27 to be disengaged from the guide rods, when it is desired to turn the side frame *d* on its pivots 24 and fold it over upon the mattress-supporting frame *e*. The guide rods 28 may be provided at their lower ends with rubber or other cushions or bumpers 32 to engage the eye-bolts 27 when the side frame is lowered into the position shown in Fig. 2.

It will be observed, that when the side frame *d* is in its raised position, it is locked against turning by the engagement of the upper end of the said side frame with the head and foot frames through the eye-bolts 27 and rods 28.

Provision is made for locking the side frame *d* in its elevated position, so as to prevent its being lowered by a child in the crib 25 pressing down upon or shaking the side frame.

In the present instance, I have shown one construction of locking device which may be preferred by me and which consists of a catch dog or lever 33 (see Figs. 1 and 6) which is pivoted at its upper end at 34 to a bracket or upright 35 attached to the mattress-supporting frame, preferably near the longitudinal center of the latter.

40 The lever 33 is provided on its inner side near its upper end with a recess 36, whose bottom wall 37 forms a catch which is designed to be engaged with the bottom cross bar or rod 21 of the movable side frame *d*.

45 The lower end of the lever or dog 33 is provided with a downwardly and outwardly inclined inner edge or surface 38, which co-operates with the cross rod 21 of the side frame *d* when the latter is lifted from its lowered position shown in Fig. 2 into its operative or elevated position shown in Fig. 1, said cross rod acting on the inclined surface 38 to automatically move the catch dog or lever outwardly until the cross rod 21

50 is lifted above the upper end of the inclined surface 38, whereupon gravity acts on the lever or dog 33 to swing it in toward the mattress-supporting frame and bring the bottom wall 37 of the recess 36 under the cross rod 21 and into position to be engaged with said cross rod when the side frame is released.

By reference to Fig. 6, it will be seen that the gravity-acting catch dog or lever serves 65 to support the movable side frame *d* in its

elevated position, and forms a most effective locking device for said side frame against accidental lowering of the side frame by a child in the crib, for the harder the child presses or leans on the side frame, the 70 tighter the catch dog or lever holds, because downward pressure on the side frame causes the catch dog or lever to move in toward the mattress supporting frame rather than away from it. The inclined inner surface of the 75 catch dog or lever 33 being downwardly and outwardly inclined affords ample space between the lower end of the dog or lever and the mattress-supporting frame for the insertion of the toe of the shoe of a person 80 standing on the floor, so as to enable the lever or dog to be forced outwardly and disengaged from the cross rod 21, thereby tripping the catch dog or lever and allowing the side frame to be lowered by gravity. 85

It will be observed that by providing a catch dog or lever which can be tripped by the foot of the operator, both hands are left free to care for the child in the crib.

From the above description, it will be 90 observed that when the crib is in use, the movable side member *d* is locked in its elevated position and is connected with the head and foot frames to form a side member having a practically fixed relation thereto. 95 When the crib is in use, the side frame *d* is capable of being lowered as above described. When the crib is not in use, it can be folded up into a small compass and into substantially the position shown in Figs. 4 and 5, 100 which is accomplished by the operator lifting the side frame *d* sufficiently to disengage the eye bolts 27 from the guide rods 28, which places the said side frame in condition to be folded over upon the mattress 40 upon 105 the mattress-supporting frame *e*, which latter is then turned on its pivots 41 (see Fig. 4), into a vertical position substantially parallel with the stationary side frame *c*, after which the members 12, 15, of the head 110 and foot frames are folded toward each other and into a position substantially parallel with the stationary side frame *c* (see Fig. 4).

By reference to Figs. 4 and 5, it will be 115 observed that the crib can be placed in a practically permanent position in a room, especially one of small size, with its rear side *c* against the wall of the room, and can be manipulated from its front side.

It is preferred to have the side frame *c* fixed to the head and foot frames as by so doing, the crib is made stronger and stiffer, but it is not desired to limit the invention in this respect.

The movable members 12, 15, of the head and foot frames are manipulated by suitable levers or jointed braces 43, 44 which are pivoted together at one end and having their opposite ends pivoted to the movable mem- 130

bers 12, 15, and to a stationary bar 45 connecting the stationary members of the head and foot frames.

The mattress-supporting frame *e* when in its horizontal or operative position, may have its front end supported by brackets 46 attached to the movable members 12, 15, of the head and foot frames.

The bar 45 may also be connected with the stationary members 10, 14, of the head and foot frames by bars 47, which form corner braces and assist in stiffening the frame of the crib.

The levers 43, 44, are arranged so as to have their opening movement limited, which may be effected by a stop 48 on one lever engaging the back of the other lever, so as to prevent the members 12, 15, from being moved beyond the proper position when turned outwardly.

I have herein shown one embodiment of the invention, but it is not desired to limit the invention to the particular construction shown.

25 **Claims.**

1. In a crib, in combination, head and foot frames provided with stationary and movable members, a side frame secured to the stationary members of said head and foot frames, a mattress-supporting frame located between said head and foot frames and pivoted to be turned into a position substantially parallel with said side frame, a side frame connected with said mattress-supporting frame to be movable bodily with relation thereto in a substantially vertical plane and to be turned over thereon to move therewith, a locking device for said movable side frame to sustain it in its elevated position, and means for connecting said movable side frame with the movable members of said head and foot frames.

2. In a crib, in combination, a mattress-supporting frame, devices having a fixed relation to said mattress-supporting frame, and a side frame pivotally connected with said devices to be turned over upon the mattress-supporting frame and bodily movable with relation to said devices and the mattress-supporting frame in a plane substantially at right angles to the latter.

3. In a crib, in combination, a mattress-

supporting frame pivoted to be turned from a substantially horizontal plane into a substantially vertical plane, devices having a 55 fixed relation to said mattress-supporting frame, and a side frame pivotally connected with said devices to be turned over upon the mattress-supporting frame and bodily movable with relation to said devices and the 60 mattress-supporting frame in a plane substantially at right angles to the latter.

4. In a crib, in combination, head and foot frames provided with stationary and movable members, a side frame secured to the 65 stationary members of said head and foot frames, a mattress-supporting frame located between said head and foot frames and pivoted to be turned into a position substantially parallel with said side frame, devices 70 having a fixed relation to said mattress-supporting frame, a side frame pivotally connected with said devices to be turned over upon the mattress-supporting frame and bodily movable with relation to said devices 75 and said mattress-supporting frame in a substantially vertical plane, means on the movable members of said head and foot frames for guiding said side frame in its vertical movement, and a locking device for said 80 movable side frame to sustain it in its elevated position.

5. In a crib, in combination, head and foot frames provided with stationary and with movable members, side frames connecting 85 said head and foot frames, a bar connecting said stationary members, and jointed braces pivoted together and to said movable members and said bar.

6. In a crib, in combination, head and foot frames, a mattress-supporting frame between said head and foot frames, devices having a fixed relation to said mattress-supporting frame, a side frame bodily movable in a substantially vertical plane with 95 relation to said mattress-supporting frame and pivoted to said devices to be turned into a position substantially parallel thereto, and means for connecting said side frame with 100 said head and foot frames.

In testimony whereof, I have signed my name to this specification.

ARTHUR F. BENT.
